UNITED STATES PATENT OFFICE.

JOHN LEWIS MILTON, OF CLEVELAND, OHIO, ASSIGNOR TO MOTOR IGNITION & DEVICES COMPANY, A CORPORATION OF WEST VIRGINIA.

TIMER FOR IGNITION APPARATUS.

1,236,590.

Specification of Letters Patent. Patented Aug. 14, 1917.

Application filed September 24, 1914. Serial No. 863,320.

To all whom it may concern:

Be it known that I, JOHN LEWIS MILTON, a citizen of the United States, residing at Cleveland, in the State of Ohio, have invented a new and useful Timer for Ignition Apparatus, of which the following is a specification.

My invention has particular reference to improvements in the timer forming a part 10 of the electric generator for which I applied for Letters Patent under the filing date of May 15, 1914, application No. 838,650. One purpose of the herein described invention is to provide an improved 15 connection between the stationary wires or cables and the adjustable member of the timer, so that the movement of the adjustable member (which occurs when the ignition is advanced or retarded) does not cause bending or twisting of said wires or cables. Such bending or twisting, as is well known, 20 is a common source of broken or loose wires in the connections to timers and like apparatus. Another purpose of the invention is 25 to improve the fulcrum of the timer lever, so as to reduce the friction at that point. In addition to the specific improvements above set forth, my invention provides improvements in minor details, whereby a 30 more substantial apparatus is produced.

Referring to the drawings:

Figure 1 is a general view of my invention.

Fig. 2 is a section along the line 2—2 of 35 Fig. 1.

Fig. 3 is a section along the line 3—3 of the Fig. 1.

Fig. 4 shows details of the timer lever spindle and manner of securing it to the 40 lever.

Fig. 5 illustrates the construction of the bearing plate and certain associated parts.

Fig. 6 is a section along the line 6—6 of 45 Fig. 1.

Fig. 7 is a view from the bottom of Fig. 1.

Fig. 8 is a view of a portion of Fig. 6 from the left.

Fig. 9 shows a circuit that may be employed.

50 Referring to Figs. 1 and 2, 1 is the body

of the timer, which forms the principal part of the stationary member. Said body contains a bearing for a shaft 2. In use the body 1 is rigidly attached to an internal combustion engine in any suitable manner. 55 It may, for example, form part of a generator which is bolted to said engine. The shaft 2 is adapted to be driven by the engine at a suitable speed relative to the speed of the engine. The particular form of timer 60 herein shown and described is suitable for a two cylinder four cycle engine, having cylinders inclined to each other, and the shaft 2 is driven at half the speed of the crank shaft. Rigidly secured to the shaft 2 65 are two cams 3 and 4. The cam 3, which is preferably of steel, is secured to the end of the shaft by means of a nut 5, the end of the shaft being tapered. The cam 4 is preferably of insulating material as fiber, for 70 reasons hereinafter given. There is an adjustable base 10, having a bearing on the end plate 1, and adapted to revolve through a limited range substantially about the axis of the shaft 2. To produce this limitation of the movement, there is a groove 1^a, in the form of an arc, in the body 1. The adjustable base 10 has a projection 10^a, extending into this groove. Said projection 10^a is preferably formed by "squirting" the metal of the base 10, the formation of the hole 10^b being incidental to this process. The abutting of the projection 10^a against the ends of the groove 1^a limits the motion of the adjustable member. The adjustable base 10, together with the hereinafter described parts which are attached thereto constitutes the adjustable member of the timer. By adjustable is meant that it may be revolved for the purpose of controlling the operation of the timer, but ordinarily remains at rest, even when the shaft 2 is being revolved.

There is a bearing plate 11 and a bracket 12, these parts being insulated from each other and from the base 10, but said base, plate and bracket are rigidly secured to one another through the rivets 13, 13 and associated insulating material 14. Additional fastening between the base 10 and bearing plate 11 is provided by the rivet 15 and as-

sociated insulation 16. There is a timer lever 20 fulcrumed at its upper end as hereinafter described. The lower end of this lever carries a contact point 21 adapted, 5 when said lever 20 is at the extreme left hand limit of its motion, to engage a contact point 22, said last named contact point being in the end of a screw 23, which screw fits in a hole tapped in a bracket 12, and is 10 prevented from turning therein by the check nut 24. The lever 20 carries a fiber block 25, adapted to be engaged by the periphery of the cam 3 whereby, when said cam occupies certain positions, said lever is forced to the 15 right against the force of the hereinafter described spring, and the contact point 21 separated from the contact point 22. To prevent excessive motion of the lever 20 at high speeds of operation, there is a buffer spring 20 26, secured to the plate 11 by the rivets 13, 13. This spring retards the motion of the lever 20 when it tends to fly an excessive amount to the right. There is a spindle 30 (see Fig. 3) rigidly secured to the end of the 25 lever 20 and adapted to rotate in the timer lever bearing 31. This bearing is rigidly secured to the bearing plate 11. There is a spring 32 coiled about the outside of the bearing 31, one end of which rests against 30 the timer lever and the other against a stud 34 rigidly secured to the plate 11. There is a retainer 35 formed from sheet steel. One end of this retainer is riveted to the outer end of the stud 34 and the other end rests 35 against the end of the spindle 30 and exerts sufficient pressure to prevent said spindle from moving outwardly.

To secure proper action of the lever 20 it is essential that there be no undue friction 40 between the end of the spindle 30 and the retainer 35. To reduce this friction, the outer end 30^a of the spindle is tapered or gradually reduced so that the contact between the retainer 35 and the end 30^a of the 45 spindle 30 is limited to an area of small diameter. To secure the best operation, however, it is desirable that the center of this area of contact between the retainer and the end of the spindle be in the center line 50 (prolonged) of the portion 30^b of the spindle 30. The portion 30^b has the form of a surface of revolution, being in the specific form shown, cylindrical. The manner of securing this is shown in Fig. 4. The spindle 55 30 which includes the portions 30^b and 30^c, shoulder 30^d and tapered end 30^a, is made in a lathe or other suitable machine so that the center of the tapered or gradually reduced end 30^a is accurately in line with the prolonged axis of the surface of revolution 30^b. The large portion of the tapered end 30^a is 60 of smaller diameter than that of the cylindrical portion 30^c. The lever 20 is placed in position on the portion 30^c, Fig. 4 illustrating

the parts after this has been done. By 65 means of a suitable tool 36, having a hollow end, the edges of the portion 30^c are flared outwardly, so as to form a shoulder which secures the lever in place on the spindle. By using a tool which does not touch the tapered end, the relative position of this end relative to the portion 30^b is not changed, and correct alinement of the end 30^a obtained.

Referring again to Fig. 1, there is a distributor lever 39, in the form of a flat spring. There is another flat spring 40 for actuating said lever. Said lever 39 and spring 40 are riveted at their right hand ends to a block 39^a. This block contains a hole through 70 which passes a bearing 43, said bearing being riveted to the bearing plate 11. Said lever 39 carries at its free end contact points 41 and 42. Rigidly associated with the adjustable base 10 by means hereinafter explained, are two contact points 43 and 44, adapted to be engaged by the contacts 41 and 42, respectively, when the lever 39 is at its lowest and its uppermost positions respectively. The lever 39 is so positioned that it 75 rests against the periphery of the cam 4, and is forced downwardly by the action of the spring 40, whereby the combined action of the cam and the spring 40 produces an up and down motion of the lever 39, so that engagement is produced alternately between the contact points 41 and 43 and between 80 42 and 44. The springiness of the lever 39 permits the cam 4 to force the middle of the lever 39 upward after the engagement of the contacts 42 and 44. If the lever 39 were rigid so that this additional upward movement of the central portion could 85 not take place, a slight inaccuracy in the relation between the cam 4, the lever 39 and the contact points 42 and 44 would be likely to cause either binding or else failure of the contacts 42 and 44 to engage. To show the manner of supporting the contact points 43 and 44 and making electrical connection 90 thereto, I will describe and show these features more particularly with reference to contact point 43, reference being made to Fig. 6. The contact point 43 is riveted to a support 45, which is secured to the adjustable base 10, but insulated therefrom by rivets 46 and associated insulating material 47. Said support 45 includes, preferably in a single piece, the ear 45^a holding the contact point 43, and the contact surface 45^b, together with the portion 45^c through which the screws pass (I shall herein use the term contact points to refer to portions which engage and disengage with practically no sliding, and contact surfaces, to portions between which sliding occurs, and which may or may not be at times separated. The term "pair" in reference to contact points or sur- 95 100 105 110 115 120 125

faces refers to two which engage each other.) There is a coöperating contact surface 48^a, forming a portion of a spring 48 secured to the stationary part of the apparatus. As the 5 adjustable base 10 and associated parts are revolved for purposes of adjustment, sliding takes place between the pair of contact surfaces 45^b and 48^a, but in use said surfaces do not become disengaged. In a similar manner 10 the contact point 44 is held in a support 49, (see Fig. 1) also secured to, but insulated from the base 10 by the aforesaid rivets 46 and insulation 47. The contact surfaces 49^b of the support 49 coöperate with 15 the stationary spring 50 in a manner similar to that described with reference to the similar parts described above.

As shown in Fig. 5, the plate 11 has a tongue 11^a. As shown in Figs. 1 and 7, the 20 bracket 12 has a tongue 12^a. The insulating material 14 which serves to insulate the plate 11 and the bracket 12 from each other and from the disk 10, also possesses a tongue 14^a, lying between the aforesaid tongues 11^a and 25 12^a as shown in Fig. 7. The tongues 11^a and 12^a constitute contact surfaces which are adapted to engage certain stationary contact surfaces hereinafter described. It will be observed that I employ but a single piece to 30 support the timer lever bearing 31 and the distributor lever bearing 43, and that this same piece also forms the tongue 11^a. By making this a single piece, I obtain much greater rigidity and durability than if I 35 used several pieces instead of the single plate 11. In a similar manner, by making the tongue 12^a an integral part of the bracket 12, I obtain durability in this member.

There are two flat springs 61 and 62, as 40 shown in Figs. 1 and 7, which are secured to the body 1 but insulated therefrom by means of screws 63 and associated insulating material 64. These springs 61 and 62 are engaged by the tongues 11^a and 12^a respectively, which enter the space between the 45 springs. During normal operation the spring 61 is always engaged by the tongue 11^a, but the spring 62 is shorter than the spring 61, and also possesses a recess 62^a, so that when 50 the adjustable member occupies such positions that the tongues occupy the positions R or R', Fig. 7, contact is made between the tongues 11^a and the spring 61, but not between the tongue 12^a and the spring 62. As 55 a part of the circuits which I may employ in connection with my invention, it is desirable to separate the tongue 12^a and the spring 62 when the adjustable member is revolved to the limit of its motion in the direction in 60 which the shaft 2 revolves. By arranging the spring 62 as shown, this spring can be employed for either direction of rotation of said shaft, making it unnecessary for the manufacturer to provide different forms of

the spring 62 for different directions of rotation. If the shaft 2 runs in a clockwise direction, as seen from the position of Fig. 1, a stop is provided for the adjustable member that the tongues can move between the positions R and A, of Fig. 7, but if said 70 shaft turns in a counter-clockwise direction, the motion of the adjustable member should be so limited that the tongues move between the positions A' and R' of Fig. 7.

In the particular form of timer which I 75 have shown herein, the cam 3 is arranged to engage and separate the contacts 21 and 22 twice during each revolution of the shaft 2. The shape of the cam 4, and its relation to the cam 3 is such that when the cam 3 80 interrupts the circuit between the contacts 21 and 22, one pair of the distributor contacts is in engagement, and at the next separation of the timer contact points, the other pair of distributor contacts is in engagement.

In the circuits which I employ it is desirable that the timer and distributor levers be insulated from the frame of the apparatus, and for this reason I have provided 85 means whereby the cams do not cause a connection between the levers on which they act and the shaft 2. This is accomplished, in the case of the cam 3, by the fiber block 25 in the timer lever 20, and in the case of the cam 4, by making said cam of insulating material. The bearing plate 11 is insulated from the adjustable base 10 by the insulation 14 and 16 as described above.

The manner of attaching the spring 48 to 90 the body of the apparatus and the cable 70 100 is shown in Figs. 6 and 8. There is an extension 1^b integral with the body 1 (its position being indicated in Fig. 1). There is an insulating block 72 to which is secured the spring 48 by means of the hollow rivet 105 73. The cable or wire 70, having the conductor 70^a and insulation 70^b extends into an opening in the insulating block 72. The insulation 70^b does not extend beyond the rivet 73, but the conductor passes through 110 said rivet and is secured thereto by solder 74. The insulating block 72 is secured to the extension 1^b of the body by means of rivets 76, 76. Said rivets may be located in the insulating block when said block is molded. Said rivets are threaded at their outer ends 115 76^a, 76^b and possess square shanks 76^b, 76^a. There is a cover 77, preferably of sheet metal, fitting over the insulating block 72, and possessing an opening through which the wire 70 passes. Said cover 77 has square openings which fit over the square shanks 76^b, and the cover is held in place by nuts and lock washers. These are removed from the upper rivet in the figures but indicated 120 by 78 and 79 respectively on the lower rivet. By means of the square holes in the cover and coöperating square shoulders on the

rivets any torque exerted on the rivets due to screwing on the nuts 78 is resisted by the cover 77, and possibility of fracturing the insulating material through strain resulting therefrom is avoided. Connection between the cable 71 and the contact surface 49^b is provided by an arrangement similar to that described above. There is also a cable 88 similarly connected to a terminal 89, which terminal, in turn, is connected to the contact spring 62.

While I do not limit the application of my invention to any particular form of circuit, I show in Fig. 9 an arrangement which may be employed. For the sake of clearness in enabling the circuits to be traced, the parts are here shown largely in diagram. There is here shown a storage battery 100, the negative terminal of which is grounded, and the positive terminal of which is connected to the wire 88. There is also shown a generator having a commutator 102, against which bear the brushes 103, 104 and 105, respectively. The brush 103 is connected through a switch 106 to the positive terminal of the storage battery 100, and the brush 104 is grounded. There is a field winding 107 connected to the brushes 103 and 105. This form of generator is typical of generators suitable for charging storage batteries at varying speeds of operation, but the particular type of the generator is not a part of the invention. The switch 106 is for the purpose of disconnecting the storage battery from the generator when the generator is at rest, and may be automatic or manually operated, as is preferred. The wire 88 is connected to the contact 62 through terminal 89, and there is a condenser 110 connected across the contact springs 61 and 62. There are shown two jump spark induction coils having the respective primary windings 120 and 121, and secondary windings 130 and 131. One end of each of the primary and each of the secondary windings is grounded, and the remaining ends of the secondary windings 130 and 131 are connected to the respective spark plugs 140 and 141. The remaining ends of the respective primary windings 120 and 121 are connected to the wires 70 and 71.

Assuming that the contacts 21 and 22 are in engagement and also that 41 and 43 are in engagement and that the position of the adjustable member is such that the spring 62 is engaged by the tongue 12^a, then the current from the battery flows through the wire 88, terminal 89, spring 62, tongue 12^a, bracket 12, contact point 22, contact point 21, lever 20, bearing plate 11, (here represented by lines only) distributor lever 39, contact points 41 and 43, contact support 45, spring 48, wire 70 and winding 120 to the ground, whence it returns to the negative

terminal of the battery. The arrows 65 show the path of this current. The arrangement of the cams is such that the contact points 21 and 22 separate while the distributor points are in engagement, and when this takes place a spark is produced at the 70 spark plug 141 in the well known manner. Had the distributor contacts 42 and 44 been in engagement, instead of 41 and 43, the current would have flowed from the lever 39 through the contact points 42 and 44, contact point support 49, spring 50, wire 71 and primary winding 121 to the ground, and the interruption of the circuit by the contact points 21 and 22 would have produced a spark at the spark plug 140. The 80 connection of the condenser 110 to the springs 61 and 62 places it in parallel with the contact points 21 and 22, where it performs the well known function of reducing the primary spark and increasing the secondary spark. When the adjustable member is turned so far in the direction of rotation of the shaft that the tongue 12^a leaves the spring 62 the flow of the battery current through the ignition system is entirely interrupted. This arrangement renders it possible to turn the ignition entirely off by means used to control the advancing and retarding of the spark, since it is merely necessary to move the adjustable member of the 90 timer sufficiently far in the direction which retards the spark in order to accomplish this.

I claim as my invention:

1. A timer for ignition apparatus including, in combination, a stationary member and an adjustable member, said adjustable member including a pair of timer contact points adapted at times to engage each other, a contact surface electrically connected with each of said timer contact points, said contact surfaces being fixed relative to the adjustable member of the timer, and said stationary member including a contact surface adapted to be engaged by each of said contact surfaces.

2. A timer for ignition apparatus including, in combination, a stationary member and an adjustable member, said adjustable member including a pair of timer contact points adapted at times to engage each other, and two contact surfaces, one connected electrically to each of said timer contact points, and said stationary member including two contact surfaces adapted to be engaged, at certain times at least, by the respective contact surfaces associated with the adjustable member, and a condenser connected across the contact surfaces associated with the stationary member.

3. A timer for ignition apparatus including, in combination a stationary member and an adjustable member, said adjustable mem-

ber including a pair of timer contact points adapted at times to engage each other, and two contact surfaces, one connected electrically to each of said timer contact points, and said stationary member including two contact surfaces, one to be engaged by each of said contact surfaces associated with said adjustable member, and a means for limiting the range of adjustability of said adjustable member whereby one of said contact surfaces associated with the stationary member is always in engagement with the coöperating contact surface associated with said adjustable member, and whereby the other of said contact surfaces associated with said stationary member becomes at times separated from the coöperating contact associated with said adjustable member.

4. A timer for ignition apparatus including, in combination, an adjustable member carrying a pair of distributor contact points and a contact surface electrically connected to one of said contact points, and a stationary member carrying a contact surface adapted to engage said first named contact surface.

5. A timer for ignition apparatus including, in combination, an adjustable member carrying a plurality of pairs of distributor contact points, and a plurality of contact surfaces, one electrically connected to one of each of said pairs of distributor contact points, and a stationary member including a plurality of contact surfaces, coöperating respectively with each of the first named contact surfaces.

6. A timer for ignition apparatus including, in combination, a timer lever, a distributor lever, a bearing for each of said levers, and a single piece to which are attached both of said bearings.

7. A timer for ignition apparatus including, in combination, a stationary member, a contact surface associated with said stationary member, an adjustable member including a timer lever, a distributor lever, a bearing for each of said levers, and a single piece carrying each of said levers and having a contact surface adapted to engage said first named contact surface.

8. A timer for ignition apparatus including, in combination, a timer lever, a distributor lever, a bearing for each of said levers, and a single flat piece carrying each of said bearings and having a contact surface.

9. A timer for ignition apparatus including a lever, a spindle for said lever, said spindle having a bearing surface in the form of a surface of revolution on one side of said lever and a gradually reduced end on the other side of said lever, the point of said gradually reduced end being in line with the axis of said bearing surface, a

hollow bearing into which said bearing surface fits, and a retainer abutting against aforesaid gradually reduced end of said spindle.

10. A timer for ignition apparatus including, in combination, a lever, a hole in said lever, a spindle passing through said hole, and having on one side of said lever a bearing surface in the form of a surface of revolution, and a shoulder between said bearing surface and said lever, and having on the other side of said lever a gradually reduced extension, and a shoulder between said gradually reduced extension and said lever, said shoulders serving to hold said spindle rigidly in place in said lever.

11. A timer for ignition apparatus including, in combination, a lever, a hole in said lever, a spindle passing through said hole and having on each side of said lever a shoulder abutting said lever, one of said shoulders being formed after said spindle is placed in the hole in said lever, and having on one side of said lever, beyond said shoulder, a bearing surface in the form of a surface of revolution, and on the other side of said lever, beyond the shoulder, a gradually reduced extension, and including a bearing for said bearing surface and a retainer abutting against the end of said gradually reduced extension.

12. A timer for ignition apparatus, including, in combination, a stationary member and an adjustable member, said adjustable member including a pair of timer contact points adapted at times to engage each other, a contact surface electrically connected with each of said timer contact points, one or more pairs of distributor contact points, and a contact surface electrically connected to one of each of said pairs of distributor contacts, and said stationary member including a contact surface adapted to be engaged by each of said contact surfaces.

13. A timer for ignition apparatus including, in combination, a stationary member and an adjustable member, said adjustable member including timer contact points adapted at times to engage each other, a contact surface electrically connected with each of said timer contact points, said contact surface being fixed in the same place relative to the adjustable member of the timer, and said stationary member including a contact surface adapted to be engaged by each of said contact surfaces.

14. A timer for ignition apparatus including, in combination, a timer lever, actuating springs, a distributor lever, a bearing for each of said levers, and a single piece to which is attached both of said springs and bearings.

15. A timer for ignition apparatus in-

cluding, in combination, a timer lever, an actuating spring, a distributor lever, a bearing for each of said levers, and a single member to which is attached both of said 5 bearings and the spring.

16. A timer for ignition apparatus including, in combination, a main timer base, two circuit breaker levers, actuating springs, a bearing for each of said levers, and a 10 single member, separate from the main

timer base, to which is attached both of said bearings and springs.

Signed at Anderson, in the county of Madison and State of Indiana, this 16th day of Sept., 1914.

JOHN LEWIS MILTON.
